BACKFIRE TORCH

Robert St. J. Orr, San Francisco, Calif.

Application April 14, 1944, Serial No. 531,695

6 Claims. (Cl. 158—10)

This invention relates to a backfire torch and has for one of its objects the provision of means in a backfire torch for eliminating the hazard of accidental explosion due to ignition of a combustible gas mixture in the torch.

Another object of the invention is the provision of a simple and reliable automatically actuatable means in a backfire torch for closing the fuel dispensing spout to flow of air therethrough into the fount or fuel supply chamber of the torch when the torch is inoperative and for opening said spout to free flow of fuel therethrough when the spout is pointed generally downwardly for dispensing liquid fuel from the torch.

A still further object of the invention is the provision of a simple improved structure in a backfire torch for protecting the spout against injury when not in use and for tightly sealing the fount of the torch against leakage during handling, such as in transit to and from a place of use, and which structure is such as to enable an operator to quickly prepare the torch for use.

Other objects and advantages will appear in the drawing and description.

It is to be understood that the drawing and description are not restrictive of the invention but are illustrative of a preferred structure.

In the drawing,

Fig. 1 is a side elevational view of a backfire torch, part of which is broken away and in section to show structure otherwise hidden.

Fig. 2 is an enlarged fragmentary sectional view of the head of the torch in inverted position with the spout depending from said head into the fount of the torch.

Fig. 3 is an enlarged fragmentary, part sectional, part elevational view of the head of the torch with the spout projecting horizontally outwardly therefrom.

In detail, the invention as illustrated in the drawing comprises an oil or fuel fount 1 that may be of heavy galvanized iron or any other suitable material. This fount is vertically elongated, having cylindrical sides, a bottom and a top. The said top is formed with an opening in which is secured an annular collar 2 that is formed with a radially inwardly projecting flange 3 for supporting a top plate 4 thereon. The collar 2 is externally threaded for a similarly internally threaded sealing ring 5. The sealing ring 5 is formed with a radially inwardly projecting flange 6 adapted to extend over the collar 2 and the marginal portion of top plate 4 for holding an oil resistant gasket 7 tightly between

the said flange, and said marginal portion and collar for sealing the assembly. Preferably said marginal portion is formed with an annular recess 8 (Figs. 1, 2). As gasket 7 is resilient, the pressure applied thereto by tightening the flange 6 of the sealing ring 5 thereagainst will force the material of the gasket into said recess for positively insuring against escape of oil past the gasket. The top plate 4 is formed with an annular flange 9 projecting axially thereof. The outer edges of said flange 9 rest on the flange 3 and which flange 3 supports said top plate with its upper surface flush with the upper edge of collar 2 (Fig. 1).

15 The top plate 4 is centrally formed with a boss 10 projecting upwardly therefrom and with a projection 11 projecting downwardly therefrom. Within boss 10 is secured the lower end of an upwardly extending spout 12, while projection 10 11 is formed with a passageway 13 that extends at an angle to end portion of spout 12 that is secured in boss 10, said passageway communicating at its upper end with the lower end of the bore 14 in spout 12.

20 The passageway 13 extends generally downwardly, although at a slant relative to the end of the bore 14 with which it communicates, and an annular ball seat 15 is intermediate the ends of said passageway for seating a ball 16 that is between said seat and the bore 14 of spout 12. As passageway 13 is of larger diameter than the bore 14 and communicates at an angle with the latter, the ball will be prevented from closing the bore 14 against flow of oil from the fount 1 to the spout when the spout is inverted or when the fount is held in operative position with the spout directed downwardly. However when the fount is upright as seen in Fig. 1, the ball is automatically seated on seat 15 by gravity.

25 The fount 1 is provided at one side with a handle 17 for manually holding and manipulating the torch, and it is important to note that when the fount is held substantially horizontal by the handle with the said handle uppermost, the inclination of passageway 13 is such that the ball 16 will automatically roll against seat 15 to trap oil in the spout. Hence the fount need not be fully restored to vertical position as in Fig. 1 to effect a seating of ball 16.

30 The spout 12 preferably extends upwardly from boss 10 coaxial with the vertical axis of fount 1, or at least parallel with such axis. Said spout is in the form of a tube, and said tube is formed adjacent its upper end with a loop 18 providing an oil trap. Said loop preferably pro-

jects to the side of the said vertical axis opposite handle 17, whereby the loop is lowermost on the spout when the fount is held horizontal or is moved through a horizontal position in manipulating the torch.

Above loop 18 the spout or tube continues parallel with the portion that extends from the loop to the fount, although said upper end of the spout may be inclined relative to the lower portion in a direction away from handle 17, if desired.

Any desired apertured discharge nozzle 19 may be provided at the upper end of the spout, which nozzle provides an aperture of the correct size for the results desired. Such nozzle may be threaded onto the upper end of the spout or otherwise removably secured thereto in any desired manner.

A wick holder 20 secured to the upper end of spout 12 above loop 18 carries an igniter wick 21 that may be drawn from the holder as it burns away, and which wick is positioned to ignite fuel oil as the latter discharges from the spout aperture.

The fount 1 is provided with a flash-proof type air inlet device 22 above handle 17 and adjacent the collar 2. This type of device is old, and is provided with a needle valve 23 adapted to open and close an aperture in a partition 24 in the body of the device. A second apertured partition 25 is in said body spaced from partition 24, and an air line 26 extends from the portion of the valve below partition 25 to a point adjacent the bottom of the fount 1. Thus upon turning the valve 23 in one direction all communication between the atmosphere and inside the fount through line 26 is closed, but upon turning the valve in the opposite direction, a communication is established through the several compartments in the device 22.

In operation, upon tilting the fount 1 to operative position in which the spout extends slantingly downwardly, the ball 16 rolls automatically away from its seat 15 permitting the fuel oil, such as kerosene for example, to flow through the spout and out of the discharge aperture in nozzle 19 for ignition by lighted wick 21. Admission of air to the fount is through the device 22, the valve 23 having previously been opened. Adjustment of valve 23 may be readily accomplished, but ignition of gas inside the fount through said device is precluded by reason of its structure.

Upon discontinuing use of the torch, the same is restored to a position in which the spout is vertical or is tilted upwardly. In either event, oil trapped in loop 18 will preclude passage of air through the spout into the fount and also discharge of gas from the fount through the spout. Also the ball 16 will automatically roll to sealing position on seat 15 further insuring against the possibility of accidental ignition of gas in the fount as well as against the formation of a dangerously combustible mixture in said fount.

When the operator is through using the torch, or the same is to be transported from one place to another for use, it is highly important that the spout be protected against injury inasmuch as the spout may be practically as long as the tank. Also the fount should be tightly sealed against leakage. This result is accomplished by unscrewing the sealing ring 5 and inverting the top plate 4 (Fig. 2) so that the spout will extend into the fount. The outer end of passageway 13 outwardly of seat 15 is threaded, and a threaded

plug 30 carried on plate 4 by a chain 31 is threaded into said outer end of the passageway 13 sealing the same. An oil-proof gasket 32 secured on plug 30 provides for an oil-proof seal. Thus the spout is protected and the fount is sealed tightly against possible leakage.

Having described the invention, I claim:

1. A torch of the character described comprising a vertically elongated oil fount having a bottom and a head closing the upper end thereof, a spout in the form of a tube extending vertically from said head and having a discharge aperture at its upper end, a handle at one side of said fount for holding the latter in tipped position with the said tube extending slantingly downwardly from said head for discharge of oil from said aperture, a loop formed in said tube adjacent said aperture providing a fuel trap, an igniter wick secured to said tube adjacent its outer end for igniting oil as discharged from the latter when the fount is in said tipped position, a gravity actuated valve at the inner end of said tube adjacent said fount movable to a position opening said tube to flow of fuel from the fount therethrough when said fount is in said tipped position and automatically movable to a position closing said tube to flow of fluid therethrough when said fount is restored to vertical position.

2. A torch of the character described comprising a vertically elongated oil fount having a bottom and a head closing the upper end thereof, a spout in the form of a tube extending vertically from said head and having a discharge aperture at its upper end, a handle at one side of said fount for holding the latter in tipped position with the said tube extending slantingly downwardly from said head for discharge of oil from said aperture, a loop formed in said tube adjacent said aperture providing a fuel trap, an igniter wick secured to said tube adjacent its outer end for igniting oil as discharged from the latter when the fount is in said tipped position, a gravity actuated valve at the inner end of said tube adjacent said fount movable to a position opening said tube to flow of fuel from the fount therethrough when said fount is in said tipped position and automatically movable to a position closing said tube to flow of fluid therethrough when said fount is restored to vertical position, said valve being so movable to said position closing said tube when said tube is horizontal in its movement from said tipped position to vertical.

3. A torch of the character described comprising a vertically elongated oil fount having a bottom and a head closing the upper end thereof, a spout in the form of a tube extending vertically from said head and having a discharge aperture at its upper end and opening into the upper end of said fount at its lower end, a handle at one side of said fount for holding the latter in tipped position with the said tube extending slantingly downwardly from said head for discharge of oil from said aperture, a loop formed in said tube adjacent said aperture providing a fuel trap, an igniter wick secured to said tube adjacent its outer end for igniting oil as discharged from the latter when the fount is in said tipped position, a gravity actuated valve at the inner end of said tube adjacent said fount movable to a position opening said tube to flow of fuel from the fount therethrough when said fount is in said tipped position and automatically movable to a position closing said tube to flow of fluid therethrough when said fount is restored to vertical position, the remainder of said tube between said loop and

said fount being straight, and said loop being offset to the side of the axis of said remainder that is opposite the side of the fount that carries said handle whereby said loop will be on the underside of said axis when the fount is in said tipped position.

4. A torch of the character described comprising a vertically elongated oil fount having a bottom and a head closing the upper end thereof, a spout in the form of a tube extending vertically from said head and having a discharge aperture at its upper end, a handle at one side of said fount for holding the latter in tipped position with the said tube extending slantingly downwardly from said head for discharge of oil from said aperture, a loop formed in said tube adjacent said aperture providing a fuel trap, an igniter wick secured to said tube adjacent its outer end for igniting oil as discharged from the latter when the fount is in said tipped position, the portion of said tube between said loop and said fount being straight, and said loop being offset to the side of the axis of said portion that is opposite the side of the fount that carries said handle whereby said loop will be on the underside of said axis when the fount is in said tipped position, and a gravity actuated check valve at the inner end of said tube adjacent said head automatically movable to a position closing said tube to flow of fuel therefrom back into said fount when said tube is substantially horizontal during movement of the fount from said tipped position back to vertical.

5. A torch of the character described comprising a vertically extending oil fount provided with an elongated oil dispensing spout projecting upwardly from its upper end, said spout being provided with a discharge aperture at its outer end, an igniter wick secured to said spout adjacent said aperture and offset to one side thereof, a gravity actuated valve in a portion of the bore of said spout closing said bore to flow of liquid

therethrough when said fount is positioned vertically with said spout extending upwardly therefrom and movable to a position opening said bore to said flow only when said fount and spout are moved to a substantially horizontally extending oil dispensing position with said wick at the under side of said aperture, said valve being automatically movable by gravity to close said bore to said flow when said fount and spout are moved from said dispensing position toward vertical and just past the position at which said valve is adapted to open.

6. A torch of the character described comprising a vertically extending oil fount provided with an elongated oil dispensing spout projecting upwardly from its upper end, said spout being provided with a discharge aperture at its outer end, an igniter wick secured to said spout adjacent said aperture and offset to one side thereof, a gravity actuated valve in a portion of the bore of said spout closing said bore to flow of liquid therethrough when said fount is positioned vertically with said spout extending upwardly therefrom and movable to a position opening said bore to said flow only when said fount and spout are moved to a substantially horizontally extending oil dispensing position with said wick at the under side of said aperture, said valve being automatically movable by gravity to close said bore to said flow when said fount and spout are moved from said dispensing position toward vertical and just past the position at which said valve is adapted to open, said valve being a ball and the said portion of said bore being inclined in a direction downwardly from the end thereof nearest said aperture when said spout is substantially horizontal with the said wick below said aperture, an annular seat for said ball positioned at the lower end of said portion when said portion is in said inclined position.
